UNITED STATES PATENT OFFICE.

G. F. CHAMBERS AND SQUIRE ROBINSON, OF WORCESTER, MASSACHUSETTS.

IMPROVEMENT IN YARN-DELIVERY APPARATUS FOR BRAIDING-MACHINES.

Specification forming part of Letters Patent No. 55,239, dated June 5, 1866.

To all whom it may concern:

Be it known that we, GEORGE F. CHAMBERS and SQUIRE ROBINSON, both of the city and county of Worcester and State of Massachusetts, have invented certain new and useful Improvements in Braiding-Machines; and we do hereby declare that the following is a full, clear, and exact description of the same, reference being had to the accompanying drawings, forming a part of this specification, in which—

Figure 1 represents a perspective view of so much of a braiding-machine as is necessary to illustrate our invention. Fig. 2 represents a longitudinal central section of Fig. 1, and Fig. 3 represents a perspective view of the parts as used prior to the application of our invention.

In the drawings, A represents the grooved base which supports the bobbin-spindle B and standard C, upon which works the thread-tension weight and stop D. In the old mode a bobbin catch-weight, E, is also employed, as shown in Fig. 3.

The grooved base A is applied to and operated in the braiding-machine in the well-known and ordinary manner. Therefore no further description of the same is necessary.

As heretofore constructed and used, the thread is passed from the bobbin F through an eye, a, in standard C, thence down between the parts b b of the tension-weight D and standard C, then up on the outside of the parts b b, and through an eye, e, in the top of standard C, to be braided with other threads in the usual manner. As the tension upon the thread increases weight D is raised until it comes in contact with the bottom of the bobbin stop-weight E, when the latter is also raised until its point d is elevated above one of the projections e, when the bobbin turns and delivers yarn.

It is designed to have the weight D fall quick enough to take up the slack of the thread and prevent the knotting thereof, while the weight E falls so as to prevent the bobbin turning more than one notch e. In practice, however, it is found that in running the machine at great speed the bobbin is liable to turn two or more notches, while the weight D does not take up under such circumstances the slack of the thread so as to prevent knotting.

Our invention obviates all the above objec-

tions, while at the same time the yarn may be braided direct from the bobbins upon which it is spun. Again, by our invention great saving of stock is effected in consequence of the more perfect and even tension upon the thread. The work, too, is more evenly and perfectly done and looks much better.

One mode in which our invention can be applied to practical use is shown in Figs. 1 and 2 of the accompanying drawings.

The weight E is not used, nor is it necessary to use a bobbin with a notched head.

Standard C is slotted or cored out to receive a lever, G, which is hinged at f, and has an eye, g, through which the thread passes. The lower end of lever G is flattened and curved to fit the head of the bobbin, while the other end of said lever has an inclined projection, h.

A metal spring, i, fastened to the standard C at j, bears or presses the lower end of lever G against the periphery of the bobbin, and thus the bobbin is held from turning by friction. The thread is passed from bobbin F through eye g, thence down under weight D, thence up and through eye e, to be braided in the usual manner.

Spring i may be attached to lever G and bear against standard C, if preferred.

The operation is as follows: As the tension of the thread increases the slack and stop weight D is raised until it reaches the position shown in black lines, Figs. 1 and 2, when the least elevation from such position causes it to press in the upper end of lever G by its action upon the inclined projection h, thereby forcing out the lower end of the same lever, which relieves the bobbin-head from friction and allows it to turn and deliver yarn. Weight D readily takes up all the slack thread. Consequently the machine can be run at great speed.

By our invention the yarn is delivered gradually and as it is braided.

Projection h may be placed lower down, if preferred.

A small screw may be passed through the lower part of standard C, in order to increase or diminish the pressure of spring i.

Weight D answers the purpose of stopping the machine when a thread breaks, as in the ordinary and common machine, but is never liable to fall and stop the machine unless the thread breaks—an occurrence quite common with the old machine, especially when it is run at high speed. The position of lever G when

R. Redd

acted upon by weight D, as above stated, is shown in red lines, Fig. 2.

Having described our improvements in braid-ing-machines, what we claim therein as new and of our invention, and desire to secure by Letters Patent, is—

1. The combination, with standard C of a friction-lever, G, substantially as and for the purposes set forth.

2. The combination, with standard C and

sliding weight D, of a friction-lever having a projection, h, as and for the purposes set forth.

3. The combination, with friction-lever G, of slide or stop and tension-weight D and spring j, substantially as set forth.

GEO. F. CHAMBERS.
SQUIRE ROBINSON.
